UNITED STATES PATENT OFFICE.

CARL PETER, OF MEDARYVILLE, INDIANA.

RAILROAD-TIE.

1,113,575.

Specification of Letters Patent. Patented Oct. 13, 1914.

Application filed July 7, 1914. Serial No. 849,461.

To all whom it may concern:

Be it known that I, CARL PETER, a citizen of Germany, residing at Medaryville, in the county of Pulaski, State of Indiana, have invented certain new and useful Improvements in Railroad-Ties; and I do hereby declare the following to be a full, clear, and exact description of the invention, such as will enable others skilled in the art to which it appertains to make and use the same.

This invention relates to improvements in railway rail ties and fastenings.

The principal object of the invention is to provide a substantial tie which will effectively support rails from sliding or sagging.

Another object is to provide simple and novel rail holding means in connection with the tie.

Other objects and advantages will be apparent from the following description, when taken in connection with the accompanying drawings.

In the drawings: Figure 1 is a side elevation of a tie showing a pair of rails mounted thereon, the rails being shown in section. Fig. 2 is a top plan view of the same. Fig. 3 is an enlarged longitudinal sectional view through the center of the tie, at one end.

Referring particularly to the accompanying drawings, the tie includes a molded plastic body 10 in which are secured the centrally disposed and longitudinally extending angle members 11. Disposed between these angle members and bolted to the depending portions thereof are metal blocks 12 so spaced apart as to receive a pair of rails 13 thereon. Formed vertically through each of the blocks are elongated openings 14, these openings being disposed at opposite sides of the base of the rail. Secured to the angle members 11 and depending therefrom are wire reinforcing elements 15, these elements being embedded in the concrete body.

Arranged to be driven downwardly through the openings 14 are the spikes 17,

these spikes having formed on one edge face the series of shoulders 18, which prevent ready withdrawal of them. The spike is provided with the usual head 19 which engages over the flange. Secured to the opposite edge face of the spike, is a leaf spring 20, this spring bearing against the opposite end wall of the opening 14 so as to force the spike against the base of the rail. The opposite end wall, that is the wall nearest the rail, is formed with a vertical series of shoulders 21 formed in opposite directions to the shoulders of the spike, and coöperating with the spike shoulders to prevent the spike moving upwardly when it is once driven in.

It will thus be seen that I have provided an effective locking device for the railway spikes which will prevent their upward movement, and such a spike as will firmly hold the rail on the tie.

What is claimed is:

A railway tie comprising a body of concrete, longitudinal angle members secured in the body and disposed in parallel relation, blocks secured between the angle members and secured thereto at distances equal to the distance between the railway rails, said blocks having vertical openings formed therethrough, one end wall of each of the openings being formed with a vertical series of shoulders, and spike members arranged to be driven through the openings, said spike members having oppositely disposed shoulders for coöperation with the shoulders of the walls of the openings, and resilient elements carried by the spike members for forcing the spike members into interlocking engagement with the shoulders of the openings.

In testimony whereof, I affix my signature, in the presence of two witnesses.

CARL PETER.
